a corporation of Delaware

Application September 27, 1930, Serial No. 484,746

4 Claims. (Cl. 62—126)

This invention relates to a refrigerating system of the compressor-condenser-expander type and more particularly to a means for returning lubricant from the refrigerating element of the compressor. In some refrigerating systems lubricant from the compressor mixes with the compressed refrigerant and passes through the condenser and into the evaporator. Due to the relatively less volatile nature of lubricants as compared with refrigerants, the latter pass from the evaporator back to the compressor through the vapor suction line, while the lubricant remains in the evaporator. In time accumulation of lubricant will be great enough to seriously impair the efficiency of the system and it will also be necessary to provide fresh lubricant to the compressor. In other refrigerating systems lubrication of the compressor is accomplished by using a so-called working fluid which consists of a refrigerant and a lubricant 10 which form a uniform mixture. In both of these systems it is necessary to provide some means for returning the lubricant from the evaporator to the compressor. A very convenient method of doing this is to introduce the lubricant from the evaporator into the vapor suction line where it is drawn along with the refrigerant vapor back to the compressor.

This invention contemplates a simple but positive means for effecting the transfer of lubricant 30 into the vapor suction line where it can be drawn back into the compressor. More specifically this invention contemplates the use of a capillary device as, for instance, a wick for transferring lubricant or a mixture of lubricant and refrigerant 35 from the evaporator into the vapor suction line to the compressor.

The invention will be more readily understood by reference to the following description taken in connection with the accompanying drawings, in 40 which

Fig. 1 is a horizontal section through an evaporator of the flooded type in which there is provided a lubricant return means contemplated by this invention;

Fig. 2 is a transverse section through the structure shown in Fig. 1;

Fig. 3, a vertical section of an evaporator showing a slightly modified arrangement of lubricant return means;

Fig. 4, a longitudinal vertical section of an evaporator of the flooded type showing a further modification of this lubricant return means;

Fig. 5, a vertical section showing the lubricant return means applied to an accumulator;

Fig. 6, a diagrammatic view of the accumulator

in a refrigerating system in which the liquid refrigerant supply to the evaporator is controlled by a high side float valve; and

Fig. 7, a detail view of the wick in Fig. 4 modified for use with a lubricant which stratifies below the refrigerant.

Referring to the drawings, the header of an evaporator of the flooded type is indicated at 1, a conduit 2 from the condenser, not shown, conveys liquid refrigerant to the evaporator where it is admitted through valve 3. Within the evaporator header is an open top or pan float 4 connected to operate valve 3 through bell crank 5 pivoted at 6 and link 7 connected to valve member 8. As the level of the liquid 9 in the header rises float 4 rises and through the linkage just described closes valve 3, and when the liquid level falls the float operates to open valve 3, thus admitting more fluid to maintain the liquid level substantially constant.

Extending into the evaporator header 1 is a vapor suction line 10 from the compressor which terminates within the open top float 4 near the bottom thereof, as illustrated. Since the open top of the float communicates directly with the vapor space above the liquid in the evaporator, vapor will be drawn into line 10 and returned to the compressor. A wick 11 extends over the edge of the pan float 4 with one end depending into the liquid 9 and the other end terminating near the bottom of the pan float. Liquid from the evaporator will be carried through this wick by capillary action over the edge of and into the pan float from whence, after it has reached a sufficient level therein, it will be sucked into the vapor line 10 and returned along with the vaporized refrigerant to the compressor. If the fluid 9 in the evaporator is a mixture of refrigerant and lubricant, some of the refrigerant will be evaporated from the mixture while going through the wick 11 over the edge of the pan and thus the liquid deposited within the pan float will contain a greater percentage of lubricant than the liquid in the evaporator. A small vent 15 is provided in line 10 to prevent liquid in float 4 from siphoning over to the compressor when it is not operating.

In Figs. 1 and 2 a chamber 12 is partitioned off in the pan float and the wick 11 transfers fluid into this chamber, which is open at the top. Instead of the liquid being sucked up directly through the opening in the end of vapor line 10, a conduit 13 is provided which communicates at one end with the suction line at 14 and has its other end extending into the chamber 12 so that

liquid transferred by wick 11 will be sucked up and carried into the flow of refrigerant vapor through line 10 back to the compressor. The chamber 12 is omitted in Fig. 3.

5 In Fig. 4 there is shown a modification of the previously described arrangements in which the evaporator header 1 is partitioned by a wall 16 which forms with the header casing a chamber 17 and a chamber 18 in open communication 10 with each other at the top of the header over partition 16. Instead of the pan float, an ordinary float 19 is provided in chamber 17 to close valve 3 when the liquid 9 rises above a pre-determined level, thus tending to maintain a substantially constant liquid level in chamber 17. On account of the partition 16 none of the liquid entering chamber 17 through valve 3 can enter chamber 18. The vapor suction line 10 extends into the header and terminates at a point near 20 the bottom of chamber 18 as illustrated. The wick 11 extends from a point below the normal liquid level in chamber 17, over the partition 16, and depends into chamber 18, and effects a transfer of a portion of the fluid in chamber 17 into 25 chamber 18 where it is sucked up into the vapor line 10 and returned to the compressor. Due to a certain amount of evaporation of the refrigerant in wick 11, the fluid transferred to chamber 18 will contain a relatively greater amount of 30 lubricant than the fluid in chamber 17.

If a lubricant is used which does not mix with the refrigerant but stratifies, it is only necessary to extend the end of the wick 11 into the lubricant stratum in the evaporator. If the specific 35 gravity of the lubricant is such that the refrigerant stratum is uppermost, as shown in Fig. 7, it will be necessary to suitably encase the wick 11 from a point above the normal liquid level to a point within the lubricant stratum with a material 20 impervious to the refrigerant. With 40 such an arrangement only lubricant will be conveyed by the wick to the chamber 18 to be sucked up by the compressor.

An accumulator 22 is shown in detail in Fig. 45 5 and comprises an outer casing 25 which forms a chamber 26 with which an expansion coil communicates through conduit 27. In Fig. 6 there is shown diagrammatically an evaporator of the flooded type comprising expansion coils 21 and 50 an accumulator 22. The admission of liquid refrigerant to the evaporator from conduit 23 is controlled by a high side float valve 24 which is well known in the art. A vapor suction line 28 from a compressor has an extension 31 projecting into chamber 26 which supports therein an 55 open top vessel 29 by some convenient means as stud bolt 30 screwed into the end of the suction line extension 31 at 32 in such a manner that the suction line terminates near the bottom of vessel 29 and the upper edge of the open top vessel 29 is above the level of the inlet opening of conduit 27 from the expansion coils. Openings 33 near the end of the suction line extension 31 allow refrigerant vapor entering the accumulator 60 from the expansion coils 21 to be withdrawn.

65 Any unevaporated refrigerant and lubricant entering the accumulator through conduit 27 will be baffled out and accumulate in chamber 26. A wick 34 extends from a point below the normal

level of the liquid accumulation in chamber 26 and extends over the edge of vessel 29 and terminates at a point near the bottom thereof. Liquid from the chamber 26 will be carried over through wick 34 into the vessel 29 where it will be sucked up by the compressor along with vaporized refrigerant through openings 33 in the vapor suction line extension 31. Here also if a lubricant is used which does not mix with the refrigerant it is only necessary to extend the wick 34 into the lubricant strata to carry over only pure lubricant which will be sucked up along with the refrigerant vapor from within vessel 29.

It will be obvious to those skilled in the art that various other changes may be made in the construction and arrangement without departing from the spirit of the invention and therefore the invention is not limited to what is shown in the drawings and described in the specification but only as indicated in the appended claims.

We claim:

1. In a refrigerating system, an expansion chamber including a header, a refrigerant inlet conduit, a control valve in said conduit, an open top hollow float responsive to the liquid level in 100 said expansion chamber for operating said control valve, a vapor outlet conduit extending into said chamber and terminating within said float, and a wick extending from within said float to a point below the normal liquid level in said expansion chamber.

2. In a refrigerating system, an evaporator including a tubular header, an inlet conduit, a control valve in said conduit, a pan float responsive to the liquid level in said header for opening and 110 closing said valve, a vapor suction line extending into said evaporator and terminating within said pan float, and a capillary liquid transfer device extending from within said pan float to a point below the normal liquid level in said evaporator.

3. A refrigerating element including a header, a liquid refrigerant conduit opening into said header, a control valve in said conduit, an open top hollow float responsive to the liquid level in 120 said header for operating said valve, means with- in the float forming a chamber open at the top, a vapor suction line extending into said header and terminating within said float, a conduit extending from said vapor suction line and terminating within said chamber and means for trans- 125 ferring liquid from the evaporator into said chamber.

4. In a refrigerating system in which a fluid consisting of refrigerant and a lubricant soluble therein is circulated, an evaporator including a 130 tubular header, a fluid inlet conduit opening into said header, a valve in said conduit, a pan float responsive to the fluid level in said header, a partition in said pan float dividing the same into two compartments, a vapor suction line extending into said evaporator header and terminating within one of said compartments, a conduit extending from said line and terminating in the other of said compartments, a wick adapted to transfer fluid over the upper edge of said pan 135 float and into the last mentioned compartment.

CLYDE E. PLOEGER.
FRANK D. PELTIER.
